UNITED STATES PATENT OFFICE.

BENJAMIN K. ACKLEY, OF CHICAGO, ILLINOIS.

HEAD-REST.

No. 851,851.

Specification of Letters Patent.

Patented April 30, 1907.

Application filed July 5, 1906. Serial No. 324,820.

To all whom it may concern:

Be it known that I, BENJAMIN K. ACKLEY, a citizen of the United States, residing at Chicago, in the county of Cook and State of Illinois, have invented certain new and useful Improvements in Head-Rests, of which the following is a specification.

This invention relates to new and useful improvements in head rests for chairs and particularly contemplates a detachable head rest capable of service with chairs of any desirable type.

The invention resides primarily in the provision of a head rest embodying a novel clamping means capable of instantaneous attachment and detachment with relation to its support.

The invention further resides in the provision of a head rest having a clamping member capable of resiliently yielding under the pressure or the weight of a person's head, without permitting of the displacement of the head rest from its support.

The invention finally aims to provide a clamping means for head rests embodying as a component and coactive element thereof a suspension means, for the head rest in a different position so as to be invisible from the front of the chair when not in use.

The detailed construction will appear in the course of the following description in which reference is had to the accompanying drawings forming a part of this specification, like numerals designating like parts throughout the several views, wherein,

Figure 1 is a perspective view illustrating the application of a head rest constructed in accordance with my invention to a chair of conventional form. Fig. 2 is a central longitudinal section thereof. Figs. 3 and 4 are

detailed perspective views of elements of the clamping means to be hereinafter specifically referred to, and Fig. 5 is a longitudinal section of a chair having the head rest supported thereon so as to be invisible from the front of said chair.

In the practical embodiment of my invention the letter A designates a chair of conventional form, to the rear face of the back of which a member 1 is secured. The member 1 constitutes the stationary element of the clamping means for the head rest and is of substantial U shape, being provided with flanges 2 parallel to the body portion of said

member and severally formed with apertures 55 for the reception of a securing means. In its disposition upon the chair A, a vertical open space 4 occurs between the member 1 and the back a of said chair. The head rest proper, designated by the letter B is of conventional form and carries a clamping element 5 which co-acts with the element 1. The element 5 comprises an elongated vertical shank 6 provided with apertures 7 through which pass fastening screws 8 to secure said element to the head rest, and a tongue 9 bent upon the shank 6 and extending at a very slight angle thereto. Owing to its proportions the tongue 9 possesses a considerable degree of resiliency. It will be readily understood that in the assemblage of the structure the major portion of the shank 6 may be covered by upholstering so as to be invisible.

In practical use, the head rest B is applied to the chair A as shown in Fig. 2, the tongue 9 and the portion of the shank 6 adjacent thereto forming a U shaped clamping element which is introduced into the recess 4. In this disposition of parts the tongue 9 bears against the element 1 and the shank 6 bears against the top bar a, and said tongue and shank serve to frictionally support the head rest B in its raised or operative position. The head rest B is capable of resiliently yielding without displacement, 85 as above intimated, owing to the resiliency of the element 5 as herein set forth. When it is desired to invert the head-rest, the element 5 is disengaged from the element 1 and the tongue 9 employed as a suspension hook 90 as is clearly shown in Fig. 5, in which position the head rest will be hidden from view by the back of the chair.

While the elements herein shown and described are well adapted to serve the functions set forth, it is obvious that various minor changes may be made in the proportions, shape and arrangement of the several parts without departing from the spirit and scope of the invention as defined in the appended claim.

Having fully described my invention I claim:

The combination with a chair and a head rest designed to be detachably secured thereto, of a U shaped clamping element carried by said chair and having its major portion spaced away therefrom, whereby an inclosed

vertical recess is afforded, and a clamping element carried by said head rest, said last named clamping element consisting of a strap having its lower end bent upon itself to afford a resilient member which frictionally engages the inner surface of said first named clamping member when inclosed therein and which in a reversed position engages the major portion of said first named clamping member as a hook. 10

In testimony whereof I affix my signature in presence of two witnesses.

BENJAMIN K. ACKLEY.
